VINCENT TANASSO, OF NEW YORK, AND JACOB J. POMERANZ, OF BROOKLYN,
NEW YORK.

DESIGN FOR A LENS CLIP OR SIMILAR ARTICLE.

Application filed February 9, 1929. Serial No. 30,005. Term of patent 14 years.

To all whom it may concern:

Be it known that we, VINCENT TANASSO and JACOB J. POMERANZ, citizens of the United States and residents respectively of the city of New York (bor. of Bronx), county of Bronx and State of New York, and of the city of New York (bor. of Brooklyn), in the county of Kings and State of New York, have invented the new, original, and ornamental Design for a Lens Clip or Similar Article, of which the following is a specification.

Figure 1 is a face view of a lens clip or

similar article showing our new design, as it appears when attached to an eyeglass lens.

Figure 2 is a perspective view of the lens clip alone.

We claim:

The ornamental design for a lens clip or similar article substantially as shown.

Signed at New York in the county of New York and State of New York this 7th day of February, A. D. 1929.

VINCENT TANASSO.
JACOB J. POMERANZ.
